UNITED STATES PATENT OFFICE.

OLUF TYBERG, OF NEW YORK, N. Y., ASSIGNOR TO RUFUS L. PATTERSON
AND GEORGE ARENTS, JR., OF NEW YORK, N. Y.

CUTTING MECHANISM FOR CIGAR-WRAPPERS.

SPECIFICATION forming part of Letters Patent No. 723,947, dated March 31, 1903.

Application filed August 30, 1902. Serial No. 121,568. (No model.)

To all whom it may concern:

Be it known that I, OLUF TYBERG, a citizen of the United States, residing at New York city county of New York, and State of New York, 5 have invented certain new and useful Improvements in Cutting Mechanisms for Cigar-Wrappers, fully described and represented in the following specification and the accompanying drawings, forming a part of the same.

The invention relates especially to mechanisms for cutting cigar wrappers or binders.

In cigar-wrapper-cutting mechanisms of the class having a cutting-die over which the leaf is laid and a coöperating roller adapted 15 to reciprocate over the die difficulty has been experienced heretofore in obtaining a proper coaction between all parts of the cutting edge of the die and the roller. Various devices have heretofore been employed for overcom- 20 ing this difficulty. The present invention aims to avoid this difficulty by providing means for shifting the die, so as to cause the roller to coöperate with a portion of its cutting edge on one stroke of its reciprocation and 25 with the remainder of the cutting edge on its return stroke. The roller will thus coact with only one cutting edge at a time, and all difficulty due to obtaining a proper coaction between the roller and the cutting edges is 30 avoided.

A full understanding of the invention can best be given by a detailed description of a construction embodying the various features thereof in the preferred form, and such a description will now be given in connection 35 with the accompanying drawings, showing such a preferred construction.

In said drawings, Figure 1 is a side view, partly in section, of a hand-machine constructed in accordance with my invention. 40 Figs. 2 and 3 are detail views showing the cutting die and roller in different positions. Fig. 4 is a bottom plan view.

Referring to the drawings, 10 represents a 45 table having an opening through which a cutting-die 11 is adapted to be projected to co-operate with a cutting-roller 12, which is carried by a pivoted arm 13. The arm 13 may be mounted in any suitable manner or as 50 usual in constructions of this class. As shown, it is mounted on adjustable journal-

screws 14. The cutting-die 11 is formed by a knife having a general elliptical form, but modified from a true ellipse to cut a wrapper of the usual or any desired form. The knife 55 is mounted on a support 15, which normally rests by means of lugs 16 on rock-shafts 17 and 18, which are mounted in hangers 19, depending from the under side of the table 10. The lugs 16 carry upwardly-extending brackets 60 20, which carry cam-studs 21 in position to be engaged by cams 22 and 23 on the rock-shafts 17 and 18, respectively. These cams 22 and 23 are formed so that when in normal position the lugs 16 are permitted to rest 65 on the rock-shafts, and the die will then be in position with its cutting edge preferably substantially flush with the surface of the table, as shown in Fig. 1.

By rocking the shafts 17 and 18 the cams 70 22 and 23 may be moved to carry their raised portions beneath the cam-studs on brackets 20, thereby raising one or the other of the edges of the die-support 15, according to which of the sets of cams has been moved into operative po- 75 sition, and thereby tilting the support and the die, as shown in Figs. 2 and 3. The cams are so formed and the rock-shafts so connected that when cams 22 are moved into position to raise one side of the die-support the cams 23 will be 80 inoperative, and vice versa. As shown, the cams 22 and 23 have their raised portions on opposite sides, and the rock-shafts are connected by means of a link 25, connecting depend- 85 ing arms on the shafts. The shafts are rocked by means of connections with the pivoted arm 13. For this purpose an oscillating yoke 26 is provided, pivotally supported beneath the table and connected by means of a link 27 90 with an arm on the shaft 17. For oscillating 90 the yoke 26 the arm 13 carries a short arm 28 beneath the table, provided with a stud 29, adapted to engage shoulders 30 and 31, re- 95 spectively, on the yoke when the arm is at or near the extremities of its oscillating move- 95 ments, and thereby slightly shift the yoke. By this construction when the arm is moved from its normal position, as shown in Fig. 1, the yoke will be thrown by engagement of the stud 29 with the shoulder 30 to rock the shafts 100 100 and cams to the position shown in Fig. 2, thereby raising the inner edge of the die into

position to coact with the roller as it moves thereover. The die will remain in this position during this reciprocation of the roller and until the stud 29 comes into engagement with the shoulder 31, whereupon the yoke will be thrown to the position shown in Fig. 4, thereby rocking the shafts in the other direction and moving the cams 22 out of operation and causing the cams 23 to act to raise the other side of the die-support to shift the die to the position shown in Fig. 3, thus bringing its other edge into position to coact with the roller. The die will then remain in this position while the roller makes the return stroke 15 of its reciprocation.

In order that the leaf may be readily placed in position on the cutting-die and properly smoothed out, it is desirable that the cutting edge of the die shall not extend above the surface of the table while the leaf is being placed in position. In order to secure this result, the yoke is provided beyond the shoulder 30 with a pocket 33, so positioned that the stud 29 may move beyond the shoulder 30 and will by such movement move the yoke into an intermediate position, in which the rock-shafts 17 and 18 and the cams 22 and 23 will be in the positions shown in Fig. 1, in which the lugs 16, extending from both sides 30 of the die-support, are allowed to rest on the rock-shafts. The die will then be in the position shown in Fig. 1, with its cutting edge substantially flush with the surface of the table. At the beginning of the movement of the arm 13 from this position the stud 29 will, by engagement with the shoulder 30, throw the yoke to bring the cutting-die into the position shown in Fig. 3 before the roller 12 reaches the end of the die.

An adjustable stop 35 is preferably provided in the yoke 26 for limiting the movement of the arm 13, and by forming the face of the elevated portion of the cams 23 slightly eccentric, as shown, this adjusting-screw 35 provides means for adjusting the amount of elevation given to the die by these cams. The surface of the elevated portion of both the cams 22 and 23 should, however, be near enough concentric with the axes of the shafts 17 and 18 so that when the cams have been shifted to raise one side of the die-support the pressure of the studs 21 on the cams will not tend to throw the cams again, and thereby permit the support to drop.

As usual in machines of this kind, a perforated platen 36 may be provided inside the cutting edges of the die, yieldingly supported by springs and limited in its upward movement by nuts on rods, as shown, and the space beneath the platen 36 may be connected with suitable exhausting apparatus through the opening 37.

It will be seen that by the construction shown, in which the die-support is supported at points beyond the limits of the die when one edge of the die-support is raised, the die will not only be tilted, so as to raise opposite

sides thereof alternately, but will be raised bodily, so as to secure a substantial projection of the cutting edges of the die above the 70 surface of the table without the necessity of too great a tilting thereof, and so that the cutting edge near the ends of the die will be sure to be in position for coaction with the roller.

It will be understood that the invention is 75 not to be limited to the exact construction and arrangements shown and to which the foregoing description has been mainly confined, but that it includes changes and modifications therein within the claims. It will 80 be understood also that while the invention has been made especially with the idea of providing an improved mechanism for cutting wrappers or binders for cigars, yet the invention or features thereof may be found useful 85 and may be employed for other purposes.

What I claim is—

1. In a cutting mechanism, the combination of a knife, a device coöperating with the knife to produce a cut, means for producing 90 a relative reciprocating movement between the coöperating cutting device and the knife, and means for shifting the knife to cause the coöperating cutting device to coöperate with one part of the knife on one stroke of the reciprocation and with the remainder of the knife during the return stroke, substantially as described.

2. In a cutting mechanism, the combination with a knife, of a device adapted to be 100 reciprocated past the knife to coöperate therewith, and means for shifting the knife to cause the coöperating cutting device to coöperate with one part of the knife on one stroke of its reciprocation and with the remainder of the knife during its return stroke, substantially as described.

3. In a cutting mechanism, the combination with a knife, of a roller adapted to be reciprocated past the knife to coöperate therewith, and means for shifting the knife to cause the roller to coöperate with a part of the knife on one stroke of its reciprocation and with the remainder of the knife during the return stroke, substantially as described.

4. The combination with a wrapper-cutting die, of a device coöperating therewith, means for producing a relative reciprocation of said members, and means for shifting the cutting-die to cause the coöperating cutting device to coöperate with a portion of the cutting-die on one stroke of the reciprocation and with the remainder of the cutting-die on the return stroke, substantially as described.

5. The combination with a wrapper-cutting die, of a roller adapted to be reciprocated over said die to coöperate therewith, and means for shifting the die to cause the roller to coöperate with one portion thereof on one stroke of its reciprocation and with the remainder thereof on the return stroke, substantially as described.

6. The combination with a wrapper-cutting die, of a device coöperating therewith, means

for producing a relative reciprocation between said members, and means for tilting the die alternately in opposite directions to cause the coöperating cutting device to co-
5 operate with one portion of the die on one stroke of the reciprocation and with the remainder of the die on the return stroke, substantially as described.

7. The combination with a wrapper-cutting die, of a roller adapted to be reciprocated over the die to coöperate therewith, and means for tilting the die alternately in opposite directions to cause the roller to coöperate with one part of the die on one stroke of its reciprocation and with the remainder of the die on its return stroke, substantially as described.

8. The combination with a wrapper-cutting die, of a roller adapted to be reciprocated over the die to coöperate therewith, and means for moving the die toward the path of the roller for coöperating therewith and for retracting the die to permit the wrapper to be placed thereover and for tilting the die alternately in opposite directions to cause the roller to coöperate with one part of the die on one stroke of its reciprocation and with the remainder of the die on its return stroke, substantially as described.

9. The combination with a table, of a wrap-
30 per-cutting die adapted to be projected through an opening in the table and normally in a retracted position, a roller adapted to reciprocate over the table to coöperate with the die, and means for tilting the die alternately in opposite directions to cause one part of its cutting edge to be projected to coöperate with the roller on one stroke of its reciprocation and the other part of its cutting edge to be projected to coöperate with the roller on its
40 return stroke, substantially as described.

10. The combination with a table, of a wrapper-cutting die adapted to be projected through an opening in the table and normally in a retracted position, a roller adapted to be reciprocated over the table to coöperate with the die, and means for raising the die bodily to project its cutting edge above the surface of the table and for tilting the die to cause the roller to coöperate with a portion of its
50 cutting edge on one stroke of its reciprocation and with the remainder of its cutting edge on the return stroke, substantially as described.

11. The combination with a wrapper-cutting die, of a roller for coöperating therewith mounted on a pivoted arm, and connections between said arm and the die whereby during the movement of the arm in one direction the die will be tilted to cause a part of its cutting
55 edge to coöperate with the roller and during the movement of the arm in the other direction the die will be tilted to cause another part of its cutting edge to coöperate with the roller, substantially as described.

65 12. The combination with a wrapper-cutting die, of a roller for coöperating therewith, a support for the roller, and connections be-

tween said support and the die whereby when the roller is at one extremity of its movement the die will be lowered and when the roller is moved in one direction the die will be raised and tilted to cause one part of its edge to coöperate with the roller and when the roller is moved in the opposite direction the die will be raised and tilted to cause another part of its edge to coöperate with the roller, substantially as described.

70 13. The combination with a wrapper-cutting die, of a roller for coöperating therewith, a support for the roller, and connections between the support and the die whereby when the roller is at one extremity of its movement the die will be in its normal position and when the roller is moved in one direction the die will be tilted to cause one part of its cutting edge to coöperate with the roller and when the roller is moved in the opposite direction the die will be tilted to cause another part of its edge to coöperate with the roller, substantially as described.

75 14. The combination with a wrapper-cutting die, of a roller for coöperating therewith, a support for the roller, a pivoted yoke 26 having shoulders 30 and 31 adapted to be engaged by a part having a movement corresponding with the movement of said support for oscillating the yoke and having a shoulder beyond the shoulder 30 adapted to be engaged by said part for moving the yoke to an intermediate position, and connections between 80 said yoke and the cutting-die whereby the die will be in its normal position when the yoke is in its intermediate position and will be tilted in one direction or the other by the movement of the yoke from its intermediate 85 position, substantially as described.

90 15. The combination with a wrapper-cutting die, of a roller adapted to be reciprocated over said die to coöperate therewith, means for tilting the die to cause the roller to coöperate with one portion thereof on one stroke of its reciprocation and with the remainder thereof on the return stroke, and means for adjusting the amount of tilting movement given to the die, substantially as 95 described.

16. The combination of a wrapper-cutting die, a support for the die normally resting on rock-shafts 17 and 18, cams 22 and 23 on said shafts, and means for rocking the shafts 100 to cause the cams to lift opposite sides of the support alternately, substantially as described.

110 17. The combination with a table, of a wrapper-cutting die adapted to be projected through an opening in the table, a roller adapted to be reciprocated over the table to coöperate with the die, and means for positively raising the die to project its cutting edge above the surface of the table during 115 the cutting movements of the roller, substantially as described.

125 18. The combination with a table, of a wrapper-cutting die adapted to be projected

- through an opening in the table, a roller adapted to be reciprocated over the table to coöperate with the die, a support for the roller, and connections between said support and
5 the die whereby the die will be lowered when the roller is at one extremity of its movement and will be positively raised during the cutting movements of the roller, substantially as described.
10 19. The combination with a table, of a wrapper-cutting die, a horizontally-swinging arm, a roller carried by said arm for coöper-

ating with the die, and a member moving with the arm and acting to raise the die during the cutting movement of the roller, substantially as described. 15

In testimony whereof I have hereunto set my hand in the presence of two subscribing witnesses.
